UNITED STATES PATENT OFFICE.

JAMES B. COLLINS, OF TULSA, OKLAHOMA.

JUMP-SEAT CANOPY.

Application filed September 1, 1927. Serial No. 216,975.

This invention relates to awnings or canopies used on motor cars, and particularly to a canopy designed to be placed over the jump or rumble seat of a motor car.

The general object of the invention is to provide a canopy which may be readily put in place or readily detached and which is so constructed that it may be supported from the back of the rumble seat and from the rear bow of the automobile top.

A further object is to provide a construction of this character which is so arranged as to detachably engage the rear bow, this connection being such that the cloth of the canopy is held in contact with the car top but permits folding.

A still further object is to provide means whereby the canopy is readily detachable from clamps which engage the car top or rear bow.

Another object is to provide means for supporting the rear corners of the canopy from the back of the jump or rumble seat, this means of support being such as to provide for a universal joint connection between the pole or cross bar which supports the rear end of the canopy and the side rods which support the sides of the canopy.

Still another object is to so form the canopy that side curtains may be readily applied if desired.

A further object is to provide means for attaching the canopy to the top of the car, which will brace it so as to prevent any shaking or vibration, which will keep the cloth straight and even, which will give the entrance side of the canopy clearance when passengers are entering or dismounting, and which will permit the canopy being readily removed for putting away when not in use.

Other objects will appear in the course of the following description.

My invention is illustrated in the accompanying drawings, wherein:—

Figure 1 is a side elevation of an automobile provided with a jump seat having my improved canopy applied thereto;

Figure 2 is a perspective view of the canopy, the back of the jump seat being broken away and the rear bow of the car being shown in dotted lines;

Figure 3 is a perspective view of the frame

of the canopy showing the frame folded in dotted lines;

Figure 4 is a perspective view of the canopy folded;

Figure 5 is a fragmentary perspective view of a rear corner of the frame;

Figure 6 is a perspective view of a canopy clamp and a portion of the canopy frame.

Referring to these drawings, it will be seen that the canopy is adapted to be applied over the jump or rumble seat A of an automobile, whose top is designated B. The back a of the rumble seat is formed with two vertically extending holes or bores C within which the rear supporting irons of the canopy are intended to be disposed.

The framework of the canopy comprises the transversely extending iron or bow 10 which at its ends is bent downward, as at 11, and twisted. Attached to the extremities of these portions 11 are the angular supporting brackets or irons 12 which are circular in cross section and whose ends are adapted to be inserted in the holes C. These irons are crank-shaped, as shown, and each iron at its upper end is connected by a pivot bolt 13 to the corresponding ear 11. Above each pivot bolt 13 each portion 11 is apertured at right angles to the pivot bolt for the passage of a bolt or rivet 14 by which a connecting link 15 is pivoted to the corresponding end 11. This link 15 is twisted and at its end is flattened to engage with a longitudinally extending, awning supporting rod 16. There are two of these rods, of course, disposed at opposite ends of the transverse bow 10 and these rods extend forward and at their ends are angularly bent, as at 17.

Coacting with these angularly bent ends are clips formed of the two clamping portions 18 and 19, the clamping portion 18 being flat and the part 19 being upwardly bowed at its middle. This part 19 forms a socket within which the angular end 17 of the corresponding rod 16 is engaged. The clamp 19 is urged toward the clamp portion 18 by means of springs 20 which surround the screws 21, these screws passing through the ends of the clamp and being engageable with the rear bow b of the automobile top. It will be seen that the clamps may be fastened to the bow in any desired position and that the rod 16

may be readily connected to or disconnected from these clamps.

Disposed upon the rods 16 and 10 is the canopy 22, which may be formed of canvas, denim, leather or any other suitable material, and which at its sides and rear is formed to provide the downwardly hanging valance 23. Inward of this valance the canopy is formed with the downwardly extending strip 10 24 of canvas which is attached at its upper edge to the canopy but has its lower edge free. This strip may carry snap fastener or other members whereby side and rear curtains may be readily attached to the canopy 15 if desired. The rear edge of the canopy is formed with the tubular hem 25 or pocket through which the rod 10 passes, and the side margins of the canopy are formed with the tubular pockets 26 within which the rods 16 20 are disposed.

Connected to the free ends of the rods 16 by cotter pins 27 is a closely coiled contractile spring 28 which passes through a hem 29 formed in the forward edge or margin of 25 the canopy. This spring yieldingly urges the rods 16 toward each other but permits the rods 16 to be spread apart beyond the parallel position and the spring 16 also acts to hold the forward margin of the curtain tightly 30 down upon the rear margin of the vehicle top so as to secure a tight contact between this margin of the curtain and the vehicle top. The universal joint constituted by the parts 11 and 15 and the bolt 14 and pivot 16 35 permits the rods 16 to be shifted freely in all directions. This permits the canopy to be adapted for any make of car having a rumble or jump seat, it permits the rods 16 to be spread apart as far as the width of the canopy will permit and upwardly inclined or disposed in a horizontal plane if necessary, and permits one of the rods to be readily disengaged from its corresponding spring clip 40 and shifted so as to permit the curtain to be folded and the occupants of the rumble seat 45 to get out of or enter the car. The spring clamp grips the angularly turned ends of the rods 16 very firmly and serves to attach the canopy to the top of the car and brace it to 50 prevent shaking and vibration. The framework with the adjustable clips engaging the rear bow of the car keep the cloth straight and even, yet permit side clearance to be secured when passengers are entering or dismounting and further permit the ready removal of the frame and canopy for putting away when not in use. The coiled spring 28, as before remarked, holds the cloth in contact with the car top and yet allows for folding 55 of the canopy for putting away when not in use.

It is to be noted that this canopy may be very readily folded up by folding the side rods 16 inward parallel to the transverse rod 10, which is permitted by the universal joint

connection between the rods 10 and the members 12, and that these supporting members 12 may be also folded into approximate parallel relation to the rod 10. Thus the canopy may be very compactly folded up for carriage or storage. 70

While I have illustrated certain details of construction and arrangement of parts, I do not wish to be limited thereto as it is obvious that many details might be changed without departing from the spirit of the invention. 75

I claim:—

1. A canopy for the jump seats of automobiles having a frame consisting of a rear bow, supporting brackets engaged with and depending from the rear bow, laterally disposed, longitudinally extending rods having flexible connection with the extremities of the rear bow and having angularly bent forward ends, clamps formed each with an upwardly 80 directed socket to receive the forward end of the corresponding latterally disposed rod, each of said clamps having means whereby it may be attached to the rear bow of an automobile top, springs urging said clamps toward closed position, and a canopy having 85 pockets along three of its side margins within which said rods and the rear bow are engaged. 90

2. A canopy for the jump seats of automobiles having a frame consisting of a rear bow, supporting brackets engaged with and depending from the rear bow, laterally disposed, longitudinally extending rods having flexible connection with the extremities of the rear bow and having angularly bent ends, 95 clamps formed each with a socket to receive the forward end of the corresponding laterally disposed rod, each of said clamps having means whereby it may be attached to the rear bow of an automobile top, springs urging 100 said clamps toward closed position, a canopy having pockets along three of its side margins within which said rods and the rear bow are engaged, the forward margin of the canopy being formed with a transversely extending pocket, and a coiled contractile spring disposed in said pocket and engaged at its ends with the lateral rods and yieldingly supporting the forward margin 105 of the canopy and adapting the forward margin of the canopy to fit snugly over the rear 110 of an automobile top. 115

3. A canopy for the jump seats of automobiles comprising a transversely extending bow, the bow at its ends being angularly bent 120 downward, angular bracket rods pivotally engaged with the depending ends of the bow and at their lower ends formed for insertion in sockets formed in the back of the jump seat, laterally disposed, longitudinally extending canopy rods having a flexible connection at their rear ends to the depending ends of the rear bow, said rods at their forward ends being angularly bent, spring clips 125 formed to provide sockets for the angularly 130

bent forward ends of the lateral rods, the clips having means whereby they may be attached to the rear bow of an automobile top, a canopy having pockets along three margins 5 through which the rear bow and the lateral rods are passed, the canopy having a transversely extending pocket along its forward margin, and a coiled contractile spring disposed in said pocket and engaged at its ends with the forward ends of the lateral rods. 10

In testimony whereof I hereunto affix my signature.

JAMES B. COLLINS.
